LATCH MECHANISM.

1,318,626.

Specification of Letters Patent.

Patented Oct. 14, 1919.

Application filed March 1, 1919. Serial No. 279,972.

To all whom it may concern:

Be it known that we, WILLIAM M. WAMPLER, a citizen of the United States, and a resident of New York, borough of Manhattan, in the county of New York and State of New York, and GEORGE E. HENRY, a citizen of Switzerland, and a resident of Bellmore, in the county of Nassau and State of New York, have made and invented certain new and useful Improvements in Latch Mechanism, of which the following is a specification.

Our invention relates to latch mechanism designed to be used with bars or gates for closing a path or passage, and particularly for use with bars or gates included in and forming a part of railing for preventing access to a space inclosed or shut off by said railing. Such gates are also used in connection with railway cars for preventing persons from proceeding in the wrong direction, and in various other places where an easily operable, and at the same time a comparatively light bar is employed for closing an opening or passage.

The object of our invention is to provide latch mechanism of the class above referred to and wherein a swinging bar is employed for closing an opening, together with latch mechanism which is normally in a position such as not to engage with the element with which it coöperates to close the opening and at the same time support one end of the bar; so that in closing a passage the operator will have to first move the bar into approximately the position it assumes when closing the passage, and then move a latch or locking member into engagement with a post or equivalent fixed support before the free end of the bar can be fixedly secured in place and the locking of the bar regarded as completely accomplished.

A further object of our invention is to provide latch mechanism wherein a swinging bar for closing a passage between two fixed posts or abutments is provided with a reciprocating and oscillating latch member at its free end, the extremity of said latch member having a locking head adapted to be moved into engagement and to be interlocked with a fixed support to thereby fasten the bar in place; but which head is normally in a position such that it will not engage with the member with which it inter-

locks, a separate act on the part of the operator, during which the latch member is moved longitudinally of the bar and its locking head into engagement with the post or abutment with which it interlocks, being necessary in order to complete the locking of the bar in place.

With the above and other objects in view, our invention consists in the improved latch mechanism illustrated in the accompanying drawing, described in the following specification, and particularly claimed, and in such variations and modifications thereof as will be obvious to those skilled in the art to which our invention relates.

In the drawing wherein the preferred embodiment of our invention is illustrated:

Figure 1 is a view showing our improved latch mechanism as seen from a position above the same, and showing also two side members or posts the opening or passage between which is adapted to be closed by the latch mechanism wherein our invention consists;

Fig. 2 is a view showing our invention as seen in side elevation, the side posts or abutments being also shown in this view;

Fig. 3 is a view upon a larger scale showing a section upon the plane indicated by the line 3—3, Fig. 1, this being a vertically extending plane, as will be appreciated;

Fig. 4 is a view similar to Fig. 3 but showing the free end of the latch member of our improved latch mechanism interlocked with the left-hand side post shown in Figs. 1 and 2; and

Fig. 5 is a view showing a section upon a transverse plane indicated by the line 5—5, Fig. 3.

Referring now to the drawing, the reference numerals 6—7 designate two upright abutments or posts the path or opening between which is closed by a movable bar 8 to thereby prevent the passage of persons between the posts, the said bar being hollow, at least for a portion of its length near its movable left-hand end, and the same being shown as in the form of a section of pipe or tube. The right-hand end of this bar is connected with the upright post 6 by means of a bracket 9 with which the end of said bar is pivotally connected as at 10 to thereby provide a permanent and fixed connection between the end of the bar in question and

the post; the character of this pivotal connection being ordinarily such that the bar may swing in both vertical and horizontal planes, as indicated by the arrows at the 5 left-hand end of the bar in Figs. 1 and 2. The reference numeral 11 designates a latch member located within the free outer end of the bar 8 and which latch member is capable of reciprocating motion along the 10 axis of said bar, and also of angular or oscillating motion about its own axis and the axis of said bar. This latch member is preferably enlarged near its outer end, as shown at 12, to approximately the same diameter 15 as that of the interior of the bar 8, in order to provide a better guide for the outer left-hand end of said member during its movements. Said latch member is further provided near its outer end with a screw threaded 20 collar 13 with which the free outer end of a sleeve 14 is in threaded engagement, and which sleeve therefore serves to cover or inclose the free outer or left-hand end of the bar 8, as clearly shown in Fig. 4; and in 25 order to prevent relative movement of the sleeve 14 and the threaded collar 13 a screw 15 is provided which extends through a hole at the left-hand end of the sleeve, and into the collar 13.

30 The left-hand free end of the latch member 12 is provided with a locking head 16, the same being comparatively thin so that when the latch member is rotated to bring the greater dimension of said head parallel and 35 into alignment with a comparatively narrow slot 17 in the upright post 7 the said head may be moved laterally and through said slot, after which and when said latch member is rotated in a reverse direction the 40 greater dimension of said head will extend across the post 7, as will be understood from Fig. 1 and as shown in Fig. 5, to thereby interlock the free end of the locking member with the said post 7.

45 The latch member 12 is operated by a spring 18 which acts both to draw the said member into the free left-hand end of the tube 8, and to rotate said member upon its axis, to thereby maintain the locking head 50 16 normally in the position in which it is shown in Fig. 2, or, as otherwise stated, in a position such that the latch member will have to be rotated throughout substantially 90° before the locking head can be inserted 55 into the slot 17 as above explained. In order to communicate both angular and longitudinal movement to the latch member the right-hand end of the spring 18 is fixedly connected with the inner end of the latch member 60 12, as indicated at 19; while the left-hand end of said spring is in a like manner fixedly secured to a fixed abutment 20 secured in place within the bar 8 by screws 21 extending into the said abutment. As shown in 65 Figs. 3 and 4, the left-hand end of the spring

is bent and extends into a hole provided in the abutment 19, as indicated at 22, although the connection between the spring and the abutment may be provided for in other ways, as will be appreciated.

The abutment 20 is provided with a central opening through which the latch member extends, and the same is prolonged to the left to provide two guides 23, 23 spaced apart from each other and between which guides a lug 70 or projection 24 carried by the latch member operates, the said guides obviously serving to limit the angular movement of the latch member by engagement of the projection 24 with the said guides.

In closing and opening between the side posts 6, 7, are equivalent fixed supports or abutments the bar 8 is first swung into approximately the position in which it is shown in Figs. 1 and 2, the normal position of the 85 locking head 16 being such that its greater dimension extends across the slot 17, as clearly shown in said figures. The operator next imparts angular movement throughout approximately 90° to the latch member 11 90 through and by means of the sleeve 14 which he grasps in his hand, thereby moving the locking head into a position such that it may be moved to the left and through the slot 17 of the post 7. When the said head 95 has been moved into a position within the post 7 the latch member is rotated in a reverse direction to cause the locking head to take up a position across the post, thus locking the free left-hand end of the latch member 100 in position and holding the bar across the opening between the posts, the locked position of the parts being shown in Fig. 4 of the drawing.

It will be appreciated that the angular 105 movement imparted to the latch member is limited by engagement of the projection or lug 24 with the guides 23, the elements referred to forming stops for limiting the extent of angular movement in both directions.

The arrangement of the spring 18 is such that the projection 24 is normally kept in contact with the upper of the guides 23, as shown in Fig. 2, irrespective of whether the 115 locking head 16 is within and interlocked with the post 7 as shown in Fig. 4, or is outside the same as shown in Figs. 1 and 2, from which it follows that the normal position of the head 16, due to the action of the 120 spring, is horizontal, as shown in Figs. 1 and 2, and that the spring will in fact return the locking head to that position after it has been rotated and moved through the slot 17 should the operator neglect to rotate 125 the latch member backward, or should he let go of it before the locking head 16 has taken the final transverse position necessary to interlock the parts shown in Fig. 4.

Having thus described and explained our 130

invention, we claim and desire to secure by Letters Patent:

1. In latch mechanism of the class described and in combination with a movable hollow bar adapted to close a passage, a reciprocating and oscillating latch member located within and at the free end of said bar and having a locking head at its free outer end; and a spring located within said bar and operatively connected with said latch member and acting to move the same into the interior of said bar.

2. In latch mechanism of the class described and in combination with a swinging hollow bar adapted to close a passage, a reciprocating and oscillating latch member located within and at the free end of said bar, and having a locking head at its free outer end; means for limiting the oscillating movement of said latch member; and a spring located within said bar and acting to impart both angular and longitudinal movement to said latch member.

3. In latch mechanism of the class described and in combination with a movable hollow bar adapted to close a passage, a reciprocating and oscillating latch member located within and at the free end of said bar and having a locking head at its free outer end; a fixed abutment located within said bar and having an opening through which said latch member extends; and a spring surrounding said latch member and the two ends of which are fixedly secured one to said abutment and the other to the inner end of said latch member.

4. In latch mechanism of the class described and in combination with a swinging hollow bar adapted to close a passage, a reciprocating and oscillating latch member located within and at the free end of said bar and having a locking head at its free outer end; a fixed abutment located within said bar and having an opening through which said latch member extends, and guides spaced apart from one another for limiting the angular movement of said latch member; a projection or lug carried by said latch member and operable between and adapted to engage the guides aforesaid at the ends of the angular movements of said latch member; and a spring surrounding said latch member and the two ends of which are fixedly secured one to said abutment and the other to the inner end of said latch member.

5. In latch mechanism of the class described and in combination with a swinging hollow bar adapted to close a passage, a reciprocating and oscillating latch member located within and at the free end of said bar and having a locking head at its free outer end; a sleeve carried by said latch member and adapted to inclose the free end of said bar; and a spring located within said bar and

operatively connected with said latch member and acting to move the same into the interior of said bar.

6. In latch mechanism of the class described and in combination with a movable hollow bar adapted to close a passage, a reciprocating and oscillating latch member located within and at the free end of said bar and having a threaded collar at its outer end and a locking head at its extremity; a sleeve surrounding the end of said bar and the outer end of which is in threaded engagement with said collar; and a spring located within said bar and acting to impart both angular and longitudinal movement to said latch member.

7. In latch mechanism of the class described and in combination with a swinging hollow bar adapted to close a passage, a reciprocating and oscillating latch member located within and at the free end of said bar and a portion of which is enlarged so as to form a close fit within the interior of said bar, said latch member having a locking head at its free outer end; a sleeve inclosing the outer end of said bar and which sleeve is connected with said latch member so as to move therewith; means for limiting oscillating movement of said latch member; and a spring located within said bar and acting to impart both angular and longitudinal movement to said latch member.

8. In latch mechanism of the class described and in combination with a swinging hollow bar adapted to close a passage, a reciprocating and oscillating latch member located within and at the free end of said bar and having a locking head at its free outer end, the outer end of said latch member being of a diameter to fit within the outer end of said bar and the same having a collar adjacent its outer end; a sleeve inclosing the outer end of said bar, and which sleeve is fixedly secured to said collar; a fixed abutment located within said bar and having an opening through which the inner end of said latch member extends; guides located within said bar and spaced apart from one another; a projection or lug carried by said latch member and operating between said guides to limit the extent of angular movement imparted to said latch member through said sleeve; and a spring surrounding the inner end of said latch member, one end of said spring being fixedly secured to said latch member and the other end thereof being fixedly secured to said abutment.

9. In latch mechanism of the class described and in combination with two abutments or supports spaced apart from each other, and a hollow bar adapted to close the passage between said abutments, one of said abutments being provided with a slot and said bar being pivotally connected with

- the other of said abutments; a reciprocating and oscillating latch member located within and at the free end of said bar and having a locking head at its free outer end, 5 the normal position of which is such that it will not contact with the abutment having said slot when said bar is moved into its closing position; and a spring located within said bar and acting to impart both 10 angular and longitudinal movement to said latch member.
10. In latch mechanism of the class described and in combination with two abutments or supports spaced apart from each 15 other, and a hollow bar adapted to close the passage between said abutments, one of said abutments being provided with a slot and said bar being pivotally connected with the other of said abutments; a reciprocating 20 and oscillating latch member located within and at the free end of said bar and having a locking head at its free outer end, the

normal position of which is such that it will not contact with the abutment having said slot when said bar is moved into its closing position; a spring located within 25 said bar and acting to impart both angular and longitudinal movement to said latch member; and a sleeve surrounding the free end of said bar and operatively connected with said latch member and through which 30 angular movement may be communicated thereto to move said locking head into position such that it may enter into said slot.

Signed at New York, borough of Manhattan, in the county of New York and State of New York this 28th day of February, A. D. 1919.

WILLIAM M. WAMPLER.
